UNITED STATES PATENT OFFICE.

FRANCIS MCF. BRINCKERHOFF, OF SUFFERN, NEW YORK, ASSIGNOR TO PRESSED STEEL CAR COMPANY, OF PITTSBURGH, PENNSYLVANIA, A CORPORATION OF NEW JERSEY.

MEANS FOR POISING THE PASSAGEWAY MEMBER IN AN ARTICULATED CAR UNIT.

Application filed March 30, 1928. Serial No. 265,878.

An object of my invention is to provide the passageway member of an articulated unit with means for returning said member to a normal position after displacement.

5 Another object of my invention is to provide the resilient means for maintaining the weather-proofing means in contact with the passageway member of an articulated car with additional resilient means for returning the passageway member to a normal position after displacement.

Another object of my invention is to provide the passageway member of an articulated car unit with resilient means attached 15 to the adjacent side of the adjacent car body and adapted to resist any displacement of the passageway member at the side towards which it is displaced and to return said member to a normal position.

20 Referring to the drawings Fig. 1 is a sectional plan view of an articulated car unit showing the relation of the passageway member to the adjacent car bodies and the method of mounting on the car bodies the 25 means for poising the passageway member between the ends of the adjacent car bodies; Fig. 2 is a section taken along the lines 2—2 of Fig. 1 and shows the means for poising the passageway member between ends of the 30 adjacent car bodies; Fig. 3 is a view showing an enlarged portion of the passageway member and the position assumed by the passageway poising means when the passageway member is displaced from a normal position; Fig. 4 is a view taken along the lines 35 2—2 of Fig. 1 and shows a modification of my invention with the additional poising means combined with the upper weather-proofing retaining means; Fig. 5 is a view 40 taken along the lines 5—5 of Fig. 4 and shows the method of attaching the passageway poising means to the adjacent car bodies; Fig. 6 is a view taken along the 45 lines 2—2 of Fig. 1 and shows the action of the passageway poising members when the passageway is displaced from a normal position.

Referring now in detail to the drawings where like reference characters refer to like parts, reference character 1 indicates an 50 articulated car unit comprising bodies 2 and 3 supported on a common truck (not shown). A passageway member 4 is pivotally supported on a bearing 5 contained on the said

truck and is poised between and extends 55 into the ends of the bodies 2 and 3. In the present embodiment of the invention the passageway member is in the form of a hollow cylinder having openings at the sides adjacent to the car bodies. At each side of the 60 passageway openings in the car bodies and in contact with the passageway member are weather-proofing means 6 which are held in contact with the passageway member by resilient means preferably near each end of the 65 weather-proofing members, said resilient means being mounted on the car bodies. These weather-proofing members and resilient means are described in detail and claimed in U. S. Pat. No. 1,644,394, granted October 4, 1927, to A. K. Pehrson, et al.

My invention consists of auxiliary members 7 placed near the top of the passageway member and having limited movement in two directions, these auxiliary members comprising portions 8 fastened to the car body and having openings 9 in which the shafts 10 of the movable members can move as the passageway member tilts with the movement of the car body. These shaft portions 10 have a stop 11 at one end which engages the portion 8 fastened to the car body and at the other end have a head 12 which bears against the weather-proofing means. It is to be understood, however, that the head 12 85 may be made to bear directly against the passageway member if desired, by removing the weather-proofing members or substituting a different type of weather-proofing means. Encircling the shaft portion 10 between the head 12 and the member 8 is a compression spring 13 which tends to keep the head 12 extended at all times. While I have described only one of the members 7, by referring to Figs. 1 and 2, it will 90 be apparent that these members 7 are at each side of the passageway openings in each of the adjacent car bodies.

By referring to Fig. 2 of the drawings it will be noted that with the two adjacent car bodies of the articulated car unit in the same horizontal plane, the passageway member is poised between the ends of the two adjacent car bodies and each of the members 7 is extended to its fullest extent and bears against the weather-proofing member. The spring 13 of the member 7 is initially compressed 105 between the head 12 and the portion 8 be-

fore assembling with the passageway member so that any movement of that member will be resisted by the compressing action caused by the movement of the passageway member against the spring 13.

When the passageway member moves away from the members 7 at one side of the car body, the head 11 of the shaft portion 10 bears against the portion 8 and prevents the outward movement of the head 12 at the other end of the shaft 10. Thus it will be readily seen that these members 7 exert a pressure on the passageway member only when that member is moved in their direction and when the passageway member is normal to both car bodies these members 7 merely have contact with the weather-proofing means as shown by Fig. 2. In this manner the passageway member, being pivotally supported at its lower end by the aforementioned base 5, is poised between the adjacent ends of two car bodies and will move in unison with the bodies when both of the bodies are moving in the same direction. When, however, during the operation of the car unit, one of the car bodies tilts to one side or the passageway member sways to one side, the passageway member moves away from the members 7 on one side and will compress the members 7 at the side towards which it is tilting. Instead of having the passageway member poised as before described, we will now have a greater pressure against one side of the passageway member than against the other side and the passageway member will immediately move to again equalize the pressure on all sides and will assume a normal position as desired.

A modification of my invention is shown in Figs. 4 and 6. Here the auxiliary members 7 are combined with the upper member of the weather-proofing operating means to form an efficient compact unit. The two spring retaining means are combined in a member 14, in the center of which is an opening or guide portion 15 and a stop portion 16 for the movable member 17 attached to the head 18 which assists in poised the passageway member. The head portion 18 has an annular flange which assists the member 14 in holding the inner spring 19 under compression at all times and builds up resistance to the movement of the passageway member by compressing the spring 19 when the passageway member moves in that direction. The outer portion of the member 14 has openings as shown by the Fig. 5 through which machine screws or other means may be inserted to permanently secure the member 14 to the car body. Contained on the member 14 within the openings for the machine screws and around the stop portion 16 is an annular depression 21 which serves to retain the spring 19 and one end of the weather-proofing operating spring

22. The other end of the spring 22 is seated in an annular flange 23 of the member 24 which is held in place against the weather-proofing members by means of lugs 25 on the member 24 which extend into openings 26 and are held there by the compressive force of the spring 22. The member 24 has an opening 27 through which the head 18 of the passageway poised member engages the weather-proofing member to control the movement of the passageway member.

As shown by Fig. 4 when the passageway member is in a position normal to the floor of the two adjacent car bodies the head 18 at each side of the passageway member is in contact with the weather-proofing means and holds the passageway member poised between the car bodies. The springs 22 and the springs at the lower end of the weather-proofing members have the same action as they have always had, and the auxiliary poised member working within the springs 22 have the same action when the passageway member is tilted as heretofore described in the preferred form of my invention.

Having thus described the invention what I claim as new and desire to secure by Letters Patent is:

1. In an articulated car unit, the adjacent ends of two adjacent bodies supported on a common truck, a passageway member poised between said bodies and spring actuated means contacting with the side of said passageway member for maintaining said passageway member in equilibrium with respect to said bodies.

2. In an articulated car unit, the adjacent ends of two adjacent bodies supported on a common truck, a passageway member between said bodies and resilient means for maintaining said passageway member in equilibrium with respect to said bodies, said means operable to exert a corrective effort during unstable equilibrium only.

3. In an articulated car unit, the adjacent ends of two adjacent bodies supported on a common truck, a passageway member between said bodies, weather-proofing means for said member, said passageway member and weather-proofing means held in an operative position by resilient means on said bodies, said resilient means operable to exert a positive centering effort when said passageway member is inclined away from a normal position with respect to said bodies.

4. In an articulated car unit, adjacent ends of two adjacent bodies supported on a common truck, a passageway member between said ends, weather-proofing means for said passageway member, said passageway member and weather-proofing means therefor being supported therebetween by spring means near the ends of said member and shorter auxiliary springs near the upper end of said passageway member.

5. In an articulated car unit, adjacent ends of two adjacent bodies supported on a common truck, a passageway member between said bodies, weather-proofing means for said member, resilient means between said bodies and passageway member for maintaining said passageway member in equilibrium with said bodies, said means comprising upper and lower members and shorter additional upper members with said additional members being attached at one end only. 6. In an articulated car unit, adjacent ends of two adjacent bodies supported on a common truck, a passageway member between said bodies, opposing spring means tending to maintain said member in a normal position and auxiliary springs operable to return said member to such position after displacement. 7. In an articulated car unit, adjacent ends of two adjacent bodies supported on a common truck, a passageway member between and extending into said bodies, weather-proofing means for said member, resilient means contained on said bodies and attached to said weather-proofing means to position said member and springs attached to said bodies and engaging said weather-proofing means, said springs operable to retard movement in their respective direction only. 8. In an articulated car unit, adjacent ends of two adjacent bodies supported on a common truck, a passageway member between and extending into said bodies, weather-proofing means at the sides of said passageway member, springs engaging said means and bodies for maintaining said passageway member in a normal position with respect to said bodies and springs attached to said bodies near the top of said means and adapted to engage said means only when the passageway member is tilted toward said last mentioned springs. 9. In an articulated car unit, adjacent ends of two adjacent bodies supported on a common truck, a passageway member between said bodies, means for maintaining said passageway member in a position normal to said bodies, said means comprising opposing springs at the end opposite the point of support and said springs being limited in movement in one direction to contact with said passageway member. 10. In an articulated car unit, adjacent ends of two adjacent bodies supported on a common truck, a passageway member between said bodies, weather-proofing means at the sides of said member, means for maintaining the weather-proofing means in contact with said passageway member and resilient members at one end of said passageway member to return said member to a normal position after displacement. 11. In an articulated car unit, means for poising the passageway member between the ends of two adjacent bodies, said means comprising a pivotal support at the base of the passageway member, and resilient means between the passageway member and car bodies at each side of the passageway openings in the car bodies, said resilient means operable to exert pressure against the passageway member only during, and to resist the tilting of said passageway member. 12. In an articulated car unit, adjacent ends of two adjacent bodies supported on a common truck, a passageway member poised between said ends, a pivotal support at the base of said passageway member, weather-proofing means between said bodies and passageway member, springs between said weather-proofing means and car ends near each end of the weather-proofing means, resilient means contained within the upper of said springs, said resilient means attached to said car bodies and limited in outward movement to contact with the weather-proofing means. 13. In an articulated car unit, adjacent ends of two adjacent bodies supported on a common truck, a passageway member poised between and extending into said adjacent ends, weather-proofing means at each side of the passageway member adjacent the car bodies, means for poising the passageway member between the ends of the two adjacent bodies, said means comprising a pivotal support at the base of the passageway member and resilient means between the weather-proofing means and car bodies, said resilient means operable to exert pressure against the weather-proofing means only during, and to resist the tilting of said passageway member. 14. In an articulated car unit, adjacent ends of two adjacent bodies supported on a common truck, a passageway member poised between said ends, a pivotal support at the base of said passageway member, springs between said passageway member and car ends near each end of the passageway member, resilient means contained within each of the upper of said springs, said resilient means attached to said car bodies and limited to outward movement to contact with the passageway member.

In testimony whereof I affix my signature.

FRANCIS McF. BRINCKERHOFF.
